UNITED STATES PATENT OFFICE.

HORATIO J. BREWER, OF NEW YORK, N. Y.

ELECTROGALVANIC BATTERY.

SPECIFICATION forming part of Letters Patent No. 660,836, dated October 30, 1900.

Application filed July 7, 1899. Serial No. 723,057. (No model.)

To all whom it may concern:

Be it known that I, HORATIO J. BREWER, a citizen of the United States, residing in the city, county, and State of New York, have 5 invented certain new and useful Improvements in Electrogalvanic Batteries, of which the following is a specification sufficient to enable others skilled in the art to which the invention appertains to make and use the 10 same.

My invention relates to galvanic batteries in which slabs of depolarizing material—such as peroxid of manganese, carbon, &c.—are used in combination with a carbon electrode 15 to form the conducting or electronegative element, as in the Leclanché battery. As heretofore used the slabs of compressed depolarizing material have been bound to electrodes in the form of flat plates of carbon 20 by means of elastic rubber bands, the resiliency of the rubber being relied upon to establish and maintain the desired contact between the opposed surfaces of carbon and conglomerate. In practice, however, the 25 rubber bands under tension rapidly deteriorate and lose their elasticity and power, resulting in looseness of contact and consequent internal resistance in the battery, and finally in the breaking of the bands and the descent 30 of the conglomerate to the bottom of the jar, rendering the battery useless. In my concurrent application, Serial No. 723,056, filed July 7, 1899, herewith, I overcome these objections to the use of slabs of conglomerate material 35 by suspending them upon a carbon electrode having inclined bearing-surfaces by means of binders, which are not necessarily elastic.

The object of my present invention is likewise to attain and maintain an intimate mechanical and electrical contact between the 40 carbon electrode and a slab or slabs of compressed depolarizing material; and the invention consists, primarily, in forming the opposed surfaces of the carbon electrode and of 45 a slab of conglomerate material in such manner that they interlock and hold the conglomerate against longitudinal or vertical displacement, and, secondarily, in combining with the interlocking plates of carbon and 50 depolarizing material binders which prevent lateral or horizontal displacement of the conglomerate and insure an intimate electrical

and mechanical contact between the opposed bearing-surfaces.

In the accompanying drawings, Figure 1 is 55 a top view of an electric battery to which my improved electronegative element has been applied. Fig. 2 is a vertical section of the battery jar and cover, showing my new conducting or electronegative element. Fig. 3 60 is a side elevation of the carbon electrode shown in Fig. 2. Fig. 4 is a vertical section of the electronegative element arranged as in Fig. 2, except that the protruding shoulders are formed upon the conglomerate slab 65 instead of upon the carbon electrode. Fig. 5 is a sectional view of the upper part of the carbon electrode and the upper part of a slab of conglomerate, showing a modification in the form of the interlocking shoulders. Fig. 70 6 is a vertical section of the electronegative element, showing another modification in form. Fig. 7 is an elevation of the inner side of one of the slabs of conglomerate shown in Fig. 6. Fig. 8 is an elevation illustrating still 75 another modification in the form of the electronegative element. Fig. 9 is an isometrical view of the inner side of one of the slabs of conglomerate shown in Fig. 8. Fig. 10 is an elevation of my electronegative element in 80 which conglomerate slabs of ordinary construction are used. Fig. 11 is an elevation of the element composed of a carbon electrode and a single slab of conglomerate.

The essential feature of the invention resting in the interlocking of the carbon electrode C, with a slab or slabs S of conglomerate depolarizing material, it is obviously immaterial whether the protruding shoulders p are on the carbon or on the conglomerate. 85 Neither is the number of slabs used in conjunction with the carbon electrode of consequence, since one conglomerate may be suspended upon the carbon, as in Fig. 11, or the electrode may be adapted to receive and support a plurality of depolarizing slabs. In any case a protruding or external shoulder p upon one part of the element is made to engage with a receding or internal shoulder r on the other. Thus in Figs. 2, 3, 5, 6, 8, and 11 the external shoulders p are formed upon the electrode C and the receding or internal shoulders upon the engaging slabs S, while in Figs. 4 and 10 illustrations are given of the 90 95 100

alternative structure, the external shoulders *p* being upon the conglomerate slabs *S* and the internal shoulders *r* upon the electrode *C*. It will be seen that in either case the result is the same, the conglomerate being suspended upon the carbon electrode *C* (in turn suspended from the cover *F* of the jar *J*) and held against longitudinal or vertical movement thereon by the interlocking of the shoulders *p* and *r*.

Binders *B*, of cord or other suitable material, may be used to secure the conglomerate to the carbon against horizontal or lateral displacement. These binders in reality secure the carbon and conglomerate against slip or derangement in any direction, since they render permanent the interlocking of the exterior shoulders *p* with the interior shoulders *r*.

The carbon electrode is supported upon the cover *F* by any desired or well known mechanical expedient, as by the collar *c*, fitting under the lugs *ee* on the neck of the carbon, as illustrated in Figs. 1 and 2.

Z is the positive or zinc electrode, applied in the usual manner.

The advantages of thus constructing and combining the parts of an electronegative element of this character are that the weight of the conglomerate is utilized in effecting and maintaining a close electrical and mechanical contact between the opposed surfaces of the external shoulder *p* and of the internal shoulder *r*; that there can be no slipping or derangement of the conglomerate either in transportation, handling, or use; that elastic binders are not essential, since the interlocking shoulders afford the requisite electrical contact independent of external or auxiliary pressure, and hence objections resulting from the deterioration of rubber binders are avoided, and that comparatively cheap simple binders of string, cord, or equivalent inelastic material may be used to secure the parts of the electronegative together in a manner that is practically permanent for the life of the battery.

It is to be understood that my present invention is essentially an improvement upon the simpler form of Leclanché battery in ordinary use, in which the conglomerate material is attached to a vertical carbon electrode by rubber bands, the tension of which is relied upon to effect the electrical contact and support the conglomerate against the vertical sides of the carbon plate.

The distinguishing feature of my invention consists in forming the parts with interlocking shoulders in such manner that the weight of the conglomerate is utilized in suspending the conglomerate on the vertical sides of the carbon plate and securing an intimate and positive electrical contact therewith, in contradistinction to the old method of relying on elastic bands to furnish sufficient frictional contact between the opposed vertical surfaces to attain the desired contact and support. It is also to be understood that the binders here-

inbefore referred to consist of surrounding bands used simply to prevent the lateral displacement of the conglomerate material suspended upon the carbon plate by preserving the engagement of the interlocking shoulders, as distinguished from bolts and other mechanical expedients for clamping the parts together. Furthermore, the interlocking shoulders herein described are integral with and are composed of the same material as the parts upon which they are formed.

What I claim as my invention, and desire to secure by Letters Patent, is—

1. In a galvanic battery, an electronegative element consisting of a vertical plate of carbon forming the electrode, and a slab of depolarizing material suspended upon said carbon plate by means of interlocking shoulders formed respectively upon the said vertical carbon plate and the slab of conglomerate, said interlocking shoulders being integral with, and of the same material as, the parts upon which they are formed, whereby the weight of the conglomerate is utilized in maintaining a close electrical contact between the carbon and conglomerate, substantially as set forth.

2. In a galvanic battery, an electronegative element consisting of a vertical plate of carbon forming the electrode, a slab of depolarizing material suspended upon said carbon plate by means of interlocking shoulders formed respectively upon the said vertical carbon plate and the slab of conglomerate, said interlocking shoulders being integral with, and of the same material as, the parts upon which they are formed, whereby the weight of the slab of conglomerate is utilized in maintaining a close electrical contact between the carbon and the conglomerate, and a retaining-band surrounding the said carbon plate and slab of conglomerate whereby the engagement of the aforesaid interlocking shoulders is maintained, substantially as herein set forth.

3. In a galvanic battery, an electronegative element consisting of a central vertical plate of carbon forming the electrode, and two slabs of conglomerate material suspended upon opposite sides of said central vertical carbon plate by means of interlocking shoulders formed respectively upon said carbon plate and the slabs of conglomerate, said interlocking shoulders being integral with, and of the same material as, the parts upon which they are formed, whereby the weight of the slabs of conglomerate is utilized in maintaining a close electrical contact between the carbon and the conglomerate, substantially as set forth.

4. In a galvanic battery, an electronegative element consisting of a central vertical plate of carbon forming the electrode, two slabs of conglomerate material suspended upon opposite sides of said vertical carbon plate by means of interlocking shoulders formed respectively upon the said carbon plate and the

slabs of conglomerate, said interlocking shoulders being integral with, and of the same material as, the parts upon which they are formed, whereby the weight of the slabs of conglomerate is utilized in maintaining a close electrical contact between the carbon and the conglomerate, and a retaining-band surrounding the said slabs of conglomerate and

the carbon plate whereby the engagement of the aforesaid interlocking shoulders is maintained, substantially as set forth.

HORATIO J. BREWER.
